(57) **CLAIM**

The ornamental design for a bicycle rack with advertisement display, as shown and described.

DESCRIPTION

FIG. 1 is a front perspective view showing a bicycle rack with advertisement display in accordance with the invention;

FIG. 2 is a front side view of FIG. 1;

FIG. 3 is a rear side view of FIG. 1;

FIG. 4 is a left side view of FIG. 1;

FIG. 5 is a right side view of FIG. 1;

FIG. 6 is a top side view of FIG. 1; and,

FIG. 7 is a bottom side view of FIG. 1.

The surface shading illustrated in the drawings is provided merely to highlight the contour of the design and is not intended to be illustrative of texture or gloss.
